Primary Examiner — Rosemary K Tarcza(74) *Attorney, Agent, or Firm* — Lerner, David, Littenberg, Krumholz & Mentlik, LLP(57) **CLAIM**

The ornamental design for a battery for portable terminal, as shown and described.

DESCRIPTION

FIG. 1 is a front perspective view of a battery for portable terminal according to our design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

Broken lines are environmental only and form no part of the claimed design.

Dash-dot lines adjacent shaded areas represent bounds of the claimed design and form no part of the claimed design themselves.

1 Claim, 4 Drawing Sheets(56)
